ANTENNA ROTATOR CONTROL HOUSING

Wayne A. Peterson, Fuquay-Varina, N.C., assignor to
Cornell-Dubilier Electric Corporation, a corporation of
Delaware

Filed Jan. 21, 1966, Ser. No. 1,170

Term of patent 14 years

(Cl. D26—14)

FIG. 1

FIG. 2

FIG. 4

FIG. 3

FIG. 5

FIG. 6

FIG. 1 is a left side, top and front perspective view of an antenna rotator control housing, showing my new design;

FIG. 2 is a front elevational view of the housing;

FIG. 3 is a plan view of the housing;

FIG. 4 is a rear elevational view of the housing;

FIG. 5 is a bottom view of the housing; and

FIG. 6 is a side elevational view of the housing.

I claim:

The ornamental design for an antenna rotator control housing, as shown.
